(57) **CLAIM**

The ornamental design for a spray bottle and towel holder, as shown and described.

DESCRIPTION

FIG. 1 illustrates a front view of the claimed design for a spray bottle and towel holder;

FIG. 2 illustrates a right-side view thereof;

FIG. 3 illustrates a left-side view thereof;

FIG. 4 illustrates a rear view thereof;

FIG. 5 illustrates a top view thereof;

FIG. 6 illustrates a bottom view thereof;

FIG. 7 illustrates a perspective view thereof; and,

FIG. 8 illustrates an exploded perspective view thereof.

The broken line showing an exemplary spray head is for illustrative purposes only and forms no part of the claimed design.
